LOCKABLE LATCH AND CATCH
CONSTRUCTION

William V. Kingdon, Indianapolis, Ind.

Application January 29, 1949, Serial No. 73,624

1 Claim. (Cl. 292—299)

1

This invention relates to a lockable latch and catch construction designed for use particularly with gates used in stockyards, and where live stock are quartered in pens or fenced areas.

It is the primary object of this invention to provide a gate latch construction of such a character that it may be locked securely in latching relation so as to prevent any unauthorized opening of the gate.

It is a further object of this invention to provide a latch construction which will automatically operate with a maximum of efficiency to latch a gate when it is closed.

It is a still further object of this invention to provide a latch construction having a member serving as a latch bar stop, thereby eliminating the use of the vertical member customarily secured to a fence post to stop the gate and prevent its swinging beyond the post.

It is a well known fact that the conventional latching means used in stockyards to secure gates in a closed position are, generally speaking, makeshift devices which require continual replacement. In addition, it is necessary for conventional latching constructions to be latched manually at a time when it is imperative that full attention be given to the head of cattle or other live stock being driven through the gate. The present invention accomplishes the latching automatically, is durable and, consequently, saves on the time and expense usually connected with their repair.

It has also been found necessary, in connection with the use of the conventional type latch, to employ a service man to repair the fence posts which serve as latch bar stop members. In the present invention, on the other hand, the use of the fence post as a stop member is eliminated, provision being made for a stop as a part of the construction of this invention.

It is desirable at times, particularly at the end of a day, to securely fasten the gate in a closed position to prevent unauthorized entrance into the alleys or pens which comprise the layout of a stockyard. The present invention employs a member as aforesaid, which is so arranged in association with the catch element that a padlock or other locking means can be used to secure the catch in locked relation.

The principal feature of the present invention resides in a member formed adjacent the latch and catch means, which serves as a stop member for the latch bar and as an anchoring member to which the catch can be locked through the use of a padlock or the like.

The full nature of the invention will be under-

2

stood from the following drawings and the accompanying description and claim:

Fig. 1 is an elevation view of a gate representative of the type used in stockyards showing the invention associated therewith.

Fig. 2 is a top plan view of the invention.

Fig. 3 is a front elevation view thereof showing the latch in locked relation.

Fig. 4 is a front elevation view showing the latch and the catch in one position during gate closing.

Fig. 5 is a side elevation view showing the latch in locked relation.

In the drawings there is shown a gate 10 representative of the type generally used in stockyards. This gate may be hinged to the fence 11 by any suitable means such as the bayonet and slot means shown at 12. Adjustably secured to the free end of the gate adjacent its upper end and extending outwardly therefrom is the latch bar 13, it having horizontally disposed slots 14 formed therein to permit its longitudinal adjustment. Bolts 15 or other suitable means extending through the slots may be employed to secure the latch bar in position. Affixed to the fence post 16 adjacent the free end of the gate is the lockable catch construction. This comprises two studs 17 having bases 18 which are affixed to the post 16 on the face thereof exposed to and confronting the free end of the gate, by the lag screws 19 or other suitable means. These screws extend through bores 20 formed in the studs.

Welded or otherwise secured to the free ends of the studs 17 is the rectangularly shaped bracket 21. This bracket comprises side and end walls joined together in such a way as to define the chamber or slot 22. The bracket is apertured as at 23 in order to receive therethrough the lag screws which, as aforesaid, extend through the studs and into the post 16.

Depending from one end of the bracket 21 is the substantially L-shaped member 24 which is the combined latch bar and padlock supporting element. This member is preferably formed integral with the bracket and the inner face of its vertically depending portion forming the base of the L serves as the latch bar stop. The arm of the L is inclined downwardly from the base thereof at an obtuse angle and thereby acts as a guide for the bar 13. If the gate should sag, the bar secured to it will still be guided up into engagement with the catch means. The arm of the L has a recess formed in its bottom portion for receiving therein the padlock 26.

Carried by the shank of one of the lag screws is

the gravity tumbler or ring 27 which is the catch means. This shank is necessarily disposed in an off-center position relative to the vertical center of the chamber or slot 22. The ring 27 carried thereby is of a size such that when it is in its normal position as shown in Fig. 3, there will be a sufficient distance between its periphery and the stop to accommodate and receive therebetween the latch bar 13.

As the gate is swung to the closed position, the latch bar extending outwardly therefrom will strike the outer portion of the ring and elevate it (see Fig. 4) in order to permit the latch bar to pass thereunder into abutting engagement with the base portion of the L-shaped member 24. When the latch bar has passed the vertical center of the ring 27, the ring or tumbler will drop downwardly to its normal position as shown in Fig. 3. In this position the latch bar 13 will be firmly enveloped and embraced in latched relation within the space separating the inner face of the stop 24 and the periphery of the ring 27. By reason of the fact that the ring is disposed in an off-center position adjacent one end of the chamber or notch 22, the latch bar will not be capable of "kicking back" from its latched position. This is true for the reason that the tumbler or ring 27 as so hung, is capable of swinging inwardly as aforesaid, but is not capable of swinging outwardly, it being stopped by the inner surface of one end of bracket 21. The only way in which the latch bar can be moved outwardly to an unlatched position is by manually elevating the ring a sufficient distance to clear the path of the latch bar.

At times it will be desirable to lock the latch construction firmly in place rather than merely to latch it. The invention is so constructed that this may be accomplished with ease and effectiveness. A recess 25 is formed in the under surface of the downwardly inclined portion of the L-shaped member 24, it being adapted to accommodate and receive therewithin the padlock body 26. The bow 28 of the padlock is extended over the L-shaped member and through the catch or ring 27 and is then secured in locked relation to the body 26. The shoulder portion 29 adjacent the recess prevents the padlock from slipping out of the recess 25 and off of the member 24. It is, of course, necessary that the padlock selected for use have a bow of a length such that when it is in locked relation the padlock will not be capable of slipping over the shoulder.

The drawings illustrate a right action gate. It is to be understood that a left action gate can readily be used if desired, merely by reversing the rectangularly shaped bracket 21 and by form-

ing the L-shaped member 24 on the inner end thereof.

While the invention has been illustrated and described in its preferred embodiment in the drawings and foregoing description, the same is to be considered as illustrative and not restrictive in character.

The invention claimed is:

In a fastener for a stockyards gate having a longitudinally adjustable latch bar projecting beyond the free end thereof and being disposed in substantially horizontal relation adjacent the top thereof, a lockable gate latch construction affixed to a fence post adjacent the free end of said gate when in closed position, said construction comprising a housing having side and end walls defining a longitudinal slot, said housing being secured in spaced relation to said fence post by at least one transversely disposed securing element, 10 said one element bridging said slot in off center position relative to the vertical center of said slot, a gravity ring loosely carried by said element and having a portion projecting below said housing, said ring being disposed substantially 15 at right angles to the longitudinal axis of said bar and laterally displaceable thereby as the gate is closed, and a substantially L-shaped member connected to the end wall of said housing which extends in the closing direction of the 20 gate, the base portion of said member depending from said end wall at substantially a right angle to said housing and being spaced rearwardly from said ring a distance sufficient to enable said bar to be interposed therebetween in gate latched 25 position, the arm portion of said member being inclined forwardly and downwardly from the bottom of said base portion and being disposed below the normal path of movement of said bar, 30 said arm portion having a downwardly exposed recess formed adjacent its free end in substantial vertical alignment with said ring, said recess being adapted to accommodate a portion of the body of a padlock used for locking said ring 35 to said arm portion.
